Primary Examiner — Karen S Acker(74) *Attorney, Agent, or Firm* — QuickPatents, Inc.; Kevin Prince(57) **CLAIM**

We claim the ornamental design for a applique, as shown and described.

DESCRIPTION

FIG. 1 is a perspective view of an applique showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a perspective view of a second embodiment of our design;

FIG. 9 is a front elevational view thereof;

FIG. 10 is a rear elevational view thereof;

FIG. 11 is a right-side elevational view thereof;

FIG. 12 is a left-side elevational view thereof;

FIG. 13 is a top plan view thereof; and,

FIG. 14 is a bottom plan view thereof.

The broken lines showing a shirt in FIG. 1 depict environmental matter and form no part of the claimed design. The remaining broken lines represent stitching, and are part of the claimed design.
